(57) CLAIM

The ornamental design for a grill, as shown and described.

DESCRIPTION

FIG. 1 is a front side perspective view of a grill;

FIG. 2 is a right side view thereof;

FIG. 3 is a left side view thereof;

FIG. 4 is a front side view thereof;

FIG. 5 is a back side view thereof;

FIG. 6 is a top view thereof; and,

FIG. 7 is a bottom view thereof.

The broken lines illustrate portions of the grill which form no part of the claimed design. Any views not shown in the figures form no part of the claimed design.

1 Claim, 5 Drawing Sheets
